UNITED STATES PATENT OFFICE.

RALPH K. MASON, OF BANTAM, CONNECTICUT.

DESIGN FOR A SAFETY-SWITCH CASING.

57,244.

Specification for Design.

Patented Mar. 8, 1921.

Application filed July 10, 1920. Serial No. 395,394. Term of patent 14 years.

To all whom it may concern:

Be it known that I, RALPH K. MASON, a citizen of the United States, residing at Bantam, in the county of Litchfield and State of Connecticut, have invented a new, original, and ornamental Design for Safety-Switch Casings, of which the following is a specification, reference being had to the accompanying drawing, forming part thereof.

Figure 1 is a perspective view.

Fig. 2 is a side elevation.

I claim:

The ornamental design for a safety switch casing, as shown.

RALPH K. MASON.
